Primary Examiner — Prabhakar Deshmukh(74) *Attorney, Agent, or Firm* — Jackson IPG PLLC(57) **CLAIM**

The ornamental design for a piston for door closer, as shown and described.

DESCRIPTION

FIG. 1 is a perspective view of a piston for door closer showing our design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a bottom plan view thereof; and,

FIG. 8 is a perspective view of a door closer with the piston disposed therein.

The broken lines in FIGS. 1–8 are for illustrative purposes only and form no part of the claimed design.
